UNITED STATES PATENT OFFICE.

CHARLES P. TOOPS, OF VALLEY JUNCTION, IOWA.

SMOKING PEDESTAL.

Application filed February 19, 1925. Serial No. 10,297.

The object of my invention is to provide a smoking pedestal or stand of simple, durable and inexpensive construction.

A further purpose of my invention is to provide such a pedestal, which will have the appearance of a slighty piece of furniture and yet which can be used for conveniently moving actuating movable top members for giving access to a tray or pan for receiving 10 smoker's articles.

A further object is to provide such a device having a removable ash reservoir preferably made in sections and provided at its upper end with a dumping ash holder adapted to be actuated for discharging by the 15 closing of the top or cover members of the device.

With these and other objects in view, my invention consists in the construction, arrangement and combination of the various 20 parts of my smoking pedestal, whereby the objects contemplated are attained, as hereinafter more fully set forth, pointed out in my claims, and illustrated in the accompanying 25 drawings, in which:

Figure 1 shows a perspective view of a smoking pedestal embodying my invention.

Figure 2 shows a top or plan view of the same with one of the cover members swung 30 to open position and the other cover member partly broken away.

Figure 3 is a vertical, sectional view taken on the line 3—3 of Figure 2.

Figure 4 is an enlarged, sectional view 35 taken on the line 4—4 of Figure 2; and

Figure 5 is an inverted, perspective view of a portion of one of the movable cover members.

It is well known that with ordinary smoking tables and the like the cigar stubs and ashes are exposed to view and the device has not the desirable appearance of a piece of furniture when it is not in use.

My improved smoking pedestal comprises an upright pedestal member indicated in the accompanying drawings by the reference numeral 10 supported on the base 11 and having at its upper end the table member 12. The table member 12 has in 45 its top a recess 13 illustrated for instance in Figure 3, in which is set a pan or tray 14 having a central opening 15 around which is an upwardly projecting annular flange 16 (see Figures 3 and 4).

50 The tray or receptacle 14 is designed to

receive cigars, tobacco, pipes, cigarettes and the like.

The table member has a central opening 17 below which is a vertically elongated recess 18 in the pedestal upright 10.

Received in the recess 18 is the lower part of a two section ash reservoir indicated generally at A and comprising the lower section 19, which is a tubular member open at its upper end and provided on 65 opposite sides with holes 20. The upper section 21 has its lower end telescopically received in the upper end of the section 19 and is provided with spring catches 23, having portions adapted to project through the 70 holes 20 for locking the sections 19 and 21 together.

At the upper end of the section 21, there is provided a horizontal exterior peripheral flange 24 terminating in a downwardly projecting flange 25 adapted to telescope over the flange 16.

Received in the upper end of the section 21 is an ash receiving hopper or the like, comprising a member 26 pivoted at its side 80 edges as at 27 to the opposite walls of said section 21.

Opposite the member 26 is a similar member 28 similarly pivoted. At the upper end of each member 26 and 28 is an upwardly 85 projecting finger 29, which when the parts are in normal position project upwardly through a notch 30 in the flange 24.

The lower portions of the members 26 and 28 are then inclined towards each other 90 for forming a closed hopper.

The pivot pintle 27 of each of the members 26 and 28 projects through the wall of the section 21 and is formed with a crank 31 as 95 shown in Figure 4.

The crank arrangement just mentioned may be varied but as here illustrated, one crank normally stands horizontally toward the other, while the other crank extends upwardly, and the ends of the crank are connected by a pivoted link 32.

A suitable spring 33 is connected with one of the pivot pintles 27 and with the link 32 for normally holding the parts in position with the hopper closed as shown in 105 Figure 3.

The parts are so arranged that when the small handles or knobs 29 are moved toward each other, they operate against the tension of the spring 33 for opening the hopper, 110

and when the handles or knobs are released, the spring 33 automatically returns the hopper to closed position.

Supported on the flange 24 are small cigar holders or trays 34.

I provide a suitable top for the smoking pedestal comprising two top or cover members 35 and 36 each forming half of the top. The member 35 is pivoted as at 37 to the table member 12 to swing in a horizontal plane and the member 36 is pivoted to the table member 12 almost diametrically opposite as at 38 to swing in a horizontal plane.

15 The adjacent faces of the top members 35 and 36 are provided with corresponding pins 39 and holes 40 so arranged that when the top members are in closed position, the pins 39 enter the holes 40, so that the pedestal may be grasped by the top and lifted without imposing twisted strain on the pivots 37 and 38.

On the under side of the top members 35 and 36, the notches 41 are cut out to enable 25 the top members to properly clear the cigar tray or holder members 34.

The top members 35 and 36 are provided on their undersides with curved grooves 42 to receive the handles or knobs 29.

30 Adjacent to the open end of each groove 42 is mounted a swinging gate 43 on a suitable pivot or pintle. Shoulders 44 at the open ends of the grooves 42 prevent the gates 43 from swinging beyond the vertical in one 35 direction, whereas the gates can swing freely in the opposite direction.

The parts just described are so arranged that when one of the top members, as for instance the member 36, is swung from its 40 open position shown at the right hand side of Figure 2 toward its closure position, the gate 43 engages the knob 29 for dumping the ash hopper.

When the closing top member reaches its 45 fully closed position, the gate 41 slides past the knob 29 for permitting the spring 33 to close the hopper.

The knob 29 will then be in the groove 42.

50 On the other hand, when the top members are swung from closed toward open position, the knobs 29 engage the gates 43 and swing them upwardly toward the position illustrated in Figure 5, so that the gates 55 thus freely clear the knobs.

In the practical use of a smoking pedestal of this kind, the user simply swings the one or both of the top members 35 and 36 to open position, places his cigars in one of 60 the trays 34 when desired, and puts his ashes into the hopper.

The member 13 is preferably of metal, so that burning ashes will not harm it.

65 The hopper may be dumped manually at any time. When the user closes the top

members 35 and 36, the hopper is automatically dumped for discharging ashes therefrom into the reservoir composed of the sections 19 and 21.

When it is desired to remove the contents 70 of the pedestal, the top members 35 and 36 may be opened and the sections 21 and 19 may be simply lifted out. They may be then taken apart by pressing the spring catches 23 inwardly for discharging the contents of the section 19.

It will be noted that when the sections 21 and 19 have been removed, the pan or tray 14 may be lifted out for removing any ashes 75 therein or for cleaning.

80 The grooves 45 are provided to receive the catches 23.

It will be seen from the foregoing that a device of this kind can be used without the necessity for frequently throwing out the 85 ashes. The ashes can be kept out of sight. The device may be used for keeping cigars and tobacco out of sight in an article that has the appearance of a piece of furniture.

Changes may be made in the details of 90 the construction and arrangement of the parts of my improved smoking pedestal without departing from the real spirit and purpose of my invention, and it is my intention to cover by my claims, any modified forms of structure or use of mechanical equivalents, which may be reasonably included within their scope.

I claim as my invention:

1. In a device of the class described, an 100 upright pedestal having a table at the upper end thereof, said table and upright pedestal being provided with a vertically, elongated opening, said table having a recess in its upper face, a tray received within said recess having a central opening, a reservoir received in said opening and projecting upwardly through said tray and a hopper for closing the reservoir, adapted to be discharged thereinto.

2. In a device of the class described, an 110 upright pedestal having a table at the top thereof, said table and upright pedestal being provided with a vertically elongated opening, said table having a recess in its upper face, a tray received within said recess having a central opening, a reservoir received in said first mentioned opening and projecting upwardly through said tray, said reservoir being made in two separable sections and an adjustable hopper above the reservoir.

3. In a device of the class described, an 120 upright pedestal having a table at the upper end thereof, said table and upright pedestal being provided with a vertically elongated opening, said table having a recess, a tray received within said recess having a central opening, a reservoir received within said opening and projecting upwardly through 130

- 5 said tray, said reservoir having at its top a dumping hopper, a swinging cover for said table, said hopper having means adapted to be engaged by the cover, whereby the swinging of the cover actuates the hopper.
4. In a device of the class described, an upright pedestal having a table at the upper end thereof, said table and upright pedestal being provided with a vertically, elongated 10 opening, said table having a recess, a tray received within said recess having a central opening, a reservoir received within said opening and projecting upwardly through said tray, said reservoir and tray having 15 coacting telescoping flanges.
5. In a device of the class described, an upright pedestal having a table at the upper end thereof, said table and upright pedestal being provided with a vertically elongated 20 opening, said table having a recess, a tray received within said recess having a central opening, a reservoir received within said opening and projecting upwardly through said tray, said reservoir and tray having
- coacting telescoping flanges, said reservoir 25 being made in two separable sections and having at its upper end a dumping hopper provided with upwardly projecting handles, pivoted cover members for said table, having means adapted to clear said handles 30 during the opening movement of the cover members and to actuate them for dumping the hopper during the closing movement of the cover members.
6. In a device of the class described, an 35 upright hollow pedestal, a reservoir therein, an openable false bottom in said reservoir adjacent the top thereof, a movable cover for said pedestal, said cover and said false bottom having coacting parts whereby the 40 movement of the cover actuates the false bottom for opening it and thereby causing the entire contents of the reservoir above the false bottom to be discharged into the portion of the reservoir below the false 45 bottom.

Des Moines, Iowa, February 14, 1925.
CHARLES P. TOOPS.
